United States Patent Office.

GEORGE H. SANBORN, OF NEW YORK, N. Y.

Letters Patent No. 84,307, dated November 24, 1868.

IMPROVEMENT IN PAPER-CUTTING MACHINES.

The Schedule referred to in these Letters Patent and making part of the same.

To all whom it may concern:

Be it known that I, GEORGE H. SANBORN, of the city, county, and State of New York, have invented a new and improved Paper-Cutting Machine; and I do hereby declare, the following to be a full and correct description of the same, reference being had to the accompanying drawings, in which—

Figure 1 is a front elevation of the machine, and Figure 2 is an end elevation of the same.

The same letter marks the same part in both figures.

The nature of the invention consists in devices for operating and checking the knife, and for giving it both an inclined and a "draw" cut, as hereinafter more fully set forth.

In the accompanying drawings—

a marks the frame of the machine, to the upper part of which the knife *c* is suspended, in proper guiding-slots, by the swinging arms *b b'*. These are not parallel to each other, the lower pivot of the arm *b* being placed a little nearer to the lower pivot of *b'* than it would be if the arms were exactly parallel. The effect of this arrangement is to lift the knife a little higher at the end suspended to arm *b*, than at the other end, so that its entire edge does not, as it descends, enter the paper at once, but by an inclined and gradual cut. The suspension of the knife by the swinging arms secures a "draw" cut, also, in the ordinary way.

The knife-stock extends out beyond the frame, as seen in fig. 1, and has a slot in its end for the reception of an adjustable block, *d*, which can be moved up and down in it by means of the set-screws *s s.* Pivoted to this nut is the rod *p*, by which the knife is operated.

A rock-shaft, *e*, is hung in brackets, *g g*, attached to the lower part of the frame, and is operated by the lever *q*, attached to its front end by its head, *f*. To this shaft is fastened the librating-arm *h*, the lower branch of which is forked to receive the lower end of connecting-rod *p*, which is pivoted to it. On the inner side of the upper end of the arm *h*, is attached a piece of rubber, *r*, adjusted by set-screw *s'*, the office of the rubber

being to check the descent of the knife, and keep it from being dulled by cutting into the table *m* when at the end of its stroke,

In rear of arm *h*, on rock-shaft *e*, is attached the segmental arm *i*, which has a grooved arc on its free end. To this is fastened a cord, *n*, which passes up over pulley *k*, and has a weight, *l*, attached to its end, as shown. The office of this weight is to raise the knife after the completion of its downward stroke.

The operation of the machine is as follows:

The paper to be cut is placed on the table *m*, the knife *c* being in its highest position, as shown in red lines in fig. 1. The lever *q* is then depressed, when the knife enters the paper at an angle with its surface, and, by a draw cut, descends through it. Just as the knife reaches the table, the rubber *r* comes into contact with the end of the frame, and checks its further descent. The lever *q* being then released, the weight *l* draws up the knife to its initial position, ready for a repetition of the operation.

Having thus fully described my invention,

What I claim, and desire to secure by Letters Patent, is—

1. The combination of the knife *c*, and the swinging arms *b b'*, when the latter are arranged, relatively to each other, in the manner described, for the purpose specified.

2. The arrangement and combination of the rod *p*, arm *h*, rock-shaft *e*, and lever *q*, as and for the purpose described.

3. The rubber *r*, attached and adjusted as described, for the purpose of arresting the motion of the knife, as set forth.

The above specification of my said invention signed and witnessed at Boston, this 22d day of September, A. D. 1868.

GEO. H. SANBORN.
